U.S. Cl. D9—219

FIG. 1.

FIG. 2.

FIG. 3.

FIG. 4.

FIG. 1 is a top plan view of a molded packaging tray for meat or the like showing our new design;

FIG. 2 is a bottom plan view;

FIG. 3 is an elevational view; and

FIG. 4 is a sectional view taken through the second row of openings in FIG. 1.

The characteristic feature of the design resides in the inverted V-shaped ribs forming the open-window bottom, which ribs merge into the side walls which have an upper portion, a curved intermediate portion and a steeply sloped bottom portion, and wherein the height of the ribs corresponds to the height of the steeply sloped bottom portion of the side walls.

We claim:

The ornamental design for a molded packaging tray for meat or the like, as shown and described.
